CLAIM

The ornamental design for a display screen portion with graphical user interface, as shown and described.

DESCRIPTION

The present application is related to U.S. Design patent application Ser. No. 29/623,813, U.S. Design patent application Ser. No. 29/623,844, U.S. Design patent application Ser. No. 29/623,815, U.S. Design patent application Ser. No. 29/623,820 and U.S. Design patent application Ser. No. 29/623,826, filed concurrently herewith, the entire disclosures of which are incorporated herein by reference.

FIG. 1 is a front view of a first embodiment of a display screen portion with graphical user interface, showing the new design;

FIG. 2 is a second embodiment thereof;

FIG. 3 is a third embodiment thereof;

FIG. 4 is a fourth embodiment thereof;

FIG. 5 is a fifth embodiment thereof; and,

FIG. 6 is a sixth embodiment thereof.

The dot-dash broken lines showing the display screen portion and all other broken lines showing portions of the graphical user interface are included for the purpose of illustrating portions of the article and form no part of the claimed design. In the figures, the perimeters of the portion of the underlying display screen and the graphical user interface are understood to be flush. Shading depicts a contrast in appearance.
